UNITED STATES PATENT OFFICE

2,439,591

SLIDE-CONTROLLED STOP MOTION

Edward Vossen, Brooklyn, N. Y., assignor to Stop-Motion Devices Corp., Brooklyn, N. Y., a corporation of New York

Application July 9, 1947, Serial No. 759,763

11 Claims. (Cl. 66—163)

1

This invention relates to new and useful improvements in stop motion devices, and particularly relates to improvements upon United States Letters Patent of W. A. Zieve, No. 2,064,869, granted December 22, 1936.

The characteristic feature of the Zieve patent resides in the fact that it is provided with a slide through which the yarn passes and which is capable of moving down to set off the stop motion device without the yarn becoming disconnected from said slide. This arrangement makes it quite simple to reset the stop motion device by merely causing the slide to again assume its raised position. The Zieve stop motion was primarily designed for knitting machines using heavier and coarser yarns than those employed in hosiery knitting machines. This invention particularly proposes to improve the Zieve stop motion to enable it to handle very fine threads like those used on ladies' hosiery. For example, from 60 denier nylon down as fine as 15 denier. This is finer than a human hair.

An important object of this invention is to provide an improved construction in which resistances of the moving parts and of the thread are materially reduced. It was an important problem to so construct the stop motion that it is sensitive and capable of handling very fine threads, and yet that it is not over-sensitive to a point where vibration or superficial pulling of the yarn will unnecessarily stop the knitting machine. The fine nylon threads used in ladies' hose travel very rapidly, and in the event of a pull it is necessary that the stop motion functions very quickly to bring the knitting machine to a halt before the very fine thread snaps and causes a damage. An important feature of this invention resides in the fact that the knitting machine will be quickly stopped in the event of a pull on the thread in excess of a superficial pull, without the stop motion dropping the thread so that it is always supported and under control, preventing twisting and entanglement around protruding parts of the knitting machine. It is pointed out that if conventional stop motion detectors are employed on a nylon or other fine thread knitting machine, the thread is pulled off the fingers of the detectors in the event of a pull, and because the thread is so very fine, it will immediately become wrapped around parts of the machine and entangled. In unentangling and unraveling of so fine a thread as from 15 to 60 denier nylon requires a great deal of patience, skill, and a relatively long time.

More specifically, the more important improve- 55 of the thread.

2

ments over the Zieve invention may be understood from the following specific objects.

It is an object of this invention to so construct the slide that the thread passes through one supporting element on the slide, for example, through an eyelet thereof. In the Zieve patent the thread was required to pass over two supporting fingers. By arranging the thread to pass through or over one support on the slide the friction is materially reduced.

It is another object of this invention to so support the slide that it is delicately balanced and guided to move in a predetermined path, preferably the vertical direction.

15 A further object is to provide a frame having parallel side rails in the nature of grooves and to construct the slide with fine side wire rails engaging in said grooves. It is proposed that the side rails of the slide be relatively long so that 20 the slide will be restrained from turning into locking positions, or positions in which friction is materially increased.

Another object of the invention resides in providing an exceptionally fine and delicate spring 25 normally urging the slide into a raised position. It is proposed to construct this spring of very fine spring steel wire wound into a spring of a very large number of turns.

The invention also proposes means for encasing and protecting the spring referred to above.

Another object of the invention is to provide a fine adjustment by which the tension of said spring may be varied for making it possible to adjust the operation of the slide to control the 35 sensitivity of the stop motion device. Thus the stop motion device may be adjusted to a point where it will not operate upon merely superficial pulls of the threads, nor will it operate due to the usual normal vibrations. The stop motion 40 may also be adjusted for different weights of yarns.

Another object of this invention is to provide separate switches for detecting an excessive pull of the yarn and for detecting a broken yarn. In 45 the Zieve patent one switch was used for both purposes. By separating the switches it is possible to use a construction in which frictional resistances and other resistances are materially reduced.

50 Another object of the invention resides in so constructing the switch which detects a broken yarn or the end of the yarn that it will be exceptionally delicate and offer substantially no resistance, or very little resistance, to the passage

Another object of the invention resides in providing a support for supporting a number of the new slide control stop motions as needed on all knitting machines.

Still another object of the invention resides in so associating the new slide control stop motion with the support so that they may be turned or aimed towards the knitting machine to direct the threads to assume more advantageous paths.

Another object is the construction of a stop motion device as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary plan view of a support provided with a group of slide control stop motion devices constructed in accordance with this invention.

Fig. 2 is a vertical sectional view taken on the line 2—2 of Fig. 1.

Fig. 3 is a side elevational view of Fig. 1.

Fig. 4 is a fragmentary enlarged view of a portion of Fig. 2.

Fig. 5 is a side view of Fig. 4.

Fig. 6 is a fragmentary enlarged vertical sectional view taken on the line 6—6 of Fig. 4.

Fig. 7 is a horizontal sectional view taken on the line 7—7 of Fig. 6.

Fig. 8 is a horizontal sectional view taken on the line 8—8 of Fig. 6.

Fig. 9 is a fragmentary enlarged detailed view of a portion of Fig. 1.

Fig. 10 is a fragmentary elevational view looking in the direction of the line 10—10 of Fig. 9.

Fig. 11 is a side view of Fig. 10.

Fig. 12 is a vertical sectional view taken on the line 12—12 of Fig. 11.

The slide control stop motion device 14, in accordance with this invention, may best be understood by first examining Figs. 4—12, inclusive. The slide control stop motion 14 includes a frame 15 having parallel side rails 16. These side rails 16 are formed with opposed grooves 17 on their opposed inner faces. The frame 15 has a bottom member 18 connecting the bottom ends of the side rails 16. This bottom member 18 is provided with a cylindrical stud 19 by which the frame 15 may be turned to various axial positions about the axis of the stud 19. The frame 15 has a top member 20 formed with slots 21 into which the top ends of the side rails 16 engage. Screws 22 attach the top ends of the side rails 16 on to the member 20.

A slide 24 is slidably mounted between said side rails 16. This slide 24 is provided with an aperture or eyelet 25 for a traveling flexible element such as a nylon thread. The eyelet 25 comprises a porcelain eyelet 25 mounted through a strip 26. This strip 26 is mounted between the top and bottom of a wire frame 27. The sides 28 of the wire frame 27 slidably engage the grooves 17. It should be noted that the sides 28 are relatively long (see Fig. 4) so as to give the slide 24 large bearing surfaces.

A tubular member 30 is mounted upon the top of the frame 15. More particularly, the bottom end of the tubular member 30 engages into a receiving slot 31 formed in the top member 20. A

75

clamp strip 32 is mounted across the top member 20 and serves to firmly hold the tubular member 30 in position. A very fine coil spring 34 of very fine spring wire having a large number of turns extends through the tubular member 30. This spring 34 has its bottom end 34' connected with the slide 24. More particularly, the end 34' passes through a small opening 35 formed in the top of the strip 26.

Spring adjustment means is mounted in the tubular member 30 and connected with the top end of the spring 34 by which the tension of the spring 34 may be controlled. This spring adjustment means includes a fine screw 36 extending through the tubular member 30. The screw 36 is rotatively supported in a block 37 mounted in the top of the tubular member 30 and held in position by a screw 38. The screw 36 has a reduced top end which passes through the block 37 and extends above said block. A friction washer 39 is engaged on the block 37 about the reduced end of the screw 36. A turning knob 40 is mounted on the top reduced end of screw 36 by which the screw 36 may be turned. A follower nut 42 threadedly engages the screw 36 and engages the inside face of the tubular member 30, which is non-circular in cross section. More specifically, the tubular member 30 and follower 42 are square. The follower 42 is provided with a reduced shank 44 around which the top end of the spring 34 is engaged and fastened.

A switch 46 is associated with the slide 24 in a certain way by which the slide 24 may control the switch 46. More particularly, the switch 46 includes a casing 47 provided with a support lug 48 attached to the top member 20 by a fastening element 49. A contact arm 50 is mounted within the casing 47 and is insulated from the casing by insulation pieces 51. These insulation pieces 51 and contact arm 50 are supported by a rivet 52. The rivet 52 also supports an external terminal 53 for an electric wire.

An operator lever 54 has a horizontal bottom section 55 turnably mounted through the bottom of the casing 47. This bottom section 55 has an upwardly directed crank-like contact portion 56 which is adapted to engage the contact arm 50 when the lever 54 pivots downwards, as indicated by the dot and dash lines in Fig. 5. The lever 54 extends upwardly along the side of the casing 47 and at the top has a top end 57 which normally engages and is raised by the slide 24.

A bottom switch 60 is associated with the top switch 46 in a certain way, hereinafter fully described. This bottom switch 60 is mounted on a member 61 having a top opening 61' for a fastening element 62 by which the switch 60 is attached to a support frame 82. The member 61 supports a traveling flexible element guide 62. This guide 62 is in the nature of a piece of U-shaped wire attached at its center to the member 61 by a fastening element 63. The guide 62 is provided with a pair of vertically spaced horizontal arms 64 and 65. These arms 64 and 65 have forwardly directed ends 66 and forwardly directed central portions 67. Said switch 60 comprises a contact arm 68 and a cooperative contact 69. The contact arm 68 is mounted within an insulation cover 70 which is mounted on the member 61 and connects with terminal 68'. The contact 69 comprises the crank portion 69 of a lever 71. This lever 71 has a bottom portion 72 engaging through the bottom of the insulation piece 70 and provided with said crank portion 69.

An insulation stud 73 is mounted upon the

member 64 and normally holds the contact arm 68 spaced from the member 61 to prevent a short circuit. The lever 71 extends up along the side of the member 61 and at the top it is provided with a horizontal top section 74 aligned between said horizontal arms 64 and 65. In the aligned positions of these parts the switch 68, 69, is open. The horizontal section 74 has a rearwardly directed central portion 75 aligned with the forwardly directed portion 67. The horizontal section 74 is also provided with a forwardly directed end 77 against which a flexible element (thread) may be engaged and by which said lever 71 may be moved rearwards and by which said flexible element (thread) may be engaged behind said forwardly directed ends 66 of said horizontal arms 64 and 65. The flexible element (thread) may be moved over to a central position to vertically pass through the aligned (eye-like) portions 67 and 75. An angle member 78 is attached to the bottom of the insulation block 70 and has a horizontal arm 79 provided with a porcelain eyelet 80 through which the traveling flexible element (thread) may move.

It is proposed that each thread of a knitting machine be protected with a slide control stop motion 14 as disclosed in Figs. 4-12, inclusive. In Figs. 1-3 a support frame 82 is illustrated supporting a number of said stop motion devices 14. The support frame 82 is provided with a bracket 83 supported by a vertical post 84 which may be mounted on the knitting machine. The support frame 82 is provided with a plurality of vertical openings 19 into which the studs 19 of the stop motion devices 14 may be engaged. For each stop motion device 14 there is a bottom switch 60 mounted in its vicinity. The threading of the stop motion device may be understood by examining Fig. 2 and noting that the thread 85' from one of the spools 85 of thread 85' of a knitting machine passes upwards through the eyelet 80 of one of the bottom switches 60, then extends upwards and through the eyelet 25 of the slide 24 of one of the stop motion devices 14, and then downwards to the knitting machine. Each thread to the knitting machine is similarly threaded.

The operation and use of the slide control stop motion may be understood from the following:

During the operation of the knitting machine the thread 85' passes very rapidly off the spool 85 and up through the eyelet 80, then through the eyelet 25 of the slide 24, and then down to the knitting machine. The spring 34 holds the slide 24 substantially stationary during the normal operation of the knitting machine overcoming superficial pulls on the thread 85' and vibrations. However, when a real obstruction to the passage of the thread 85' comes along, the thread will be pulled and the slide 24 will be pulled down along the rails 16. As soon as the slide 24 moves downwards, the lever 54 will be released and will move downwards due to gravity. The contact crank 56 of the lever 54 will move forwards and engage the contact arm 50. This closes the electric circuit of the switch 46. It is proposed that all of the switches 46 of all of the stop motion devices 14 be connected in the electric stop motion system of the knitting machine so that as soon as any switch 46 is closed the controller of the knitting machine is actuated and the knitting machine instantly stops. The operator then investigates the cause of the pull and makes suitable adjustment and repair.

It should be particularly noted that the stop 75 flexible element past said second named operator

motion device 14 functioned without the thread 85' being dropped. The thread 85' is still passing through the eyelet 25. It is therefore supported. It did not fall down as in a customary finger type stop motion, and consequently there is no opportunity for the thread to become entangled. The knitting machine may be restarted merely by loosening the pull on the yarn 85' so that the spring 34 returns the slide 24 to its raised position. The slide 24 then lifts the lever 54 so that the crank contact 56 disengages the contact arm 50.

In the event that the yarn 85' breaks or runs out, without a pull which operates the slide 24, then the lever 71 is released as soon as no yarn passes through the projecting (eye-like) portions 67 and 75. The lever 71 is therefore freed and falls down, as indicated by the dot and dash lines 71 in Fig. 10. The crank contact 69 will then engage the contact arm 68, closing the switch 69. It should be understood that all switches 60 are to be connected with the electric controller of the knitting machine so that the knitting machine is instantly stopped.

The switch 60 may easily be rethreaded. It is merely necessary that the thread be engaged at the base of the forwardly extending end portion 77 of the horizontal section 74 of the lever 71. The lever 71 is then moved backwards until the thread reaches a position in back of the forwardly engaged ends 66 of the guide 62. Now the thread may be moved laterally behind the guide 62 until it reaches a position between the eye-like projections 67 and 75. The switch 60 is now in its operative position again.

The tension of the spring 34 may be varied by turning the knob 40, causing the following nut 42 to move upwards or downwards for stretching or releasing the spring 34. This controls the sensitivity of the stop motion device so that it may be adjusted to avoid operations due to superficial pulls and vibration. Each of the slide control stop motion devices 14 may be turned about the studs 19 as an axis so as to properly direct the thread passing through the eyelet 25 to the knitting machine.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to have secured by Letters Patent is:

1. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator

lever for holding it raised and so holding said second named switch open.

2. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator lever for holding it raised and so holding said second named switch open, said side rails having grooves in which said slide operates.

3. A slide-controlled stop motion, comprising a frame having parallel side rails, a slide having an aperture for traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator lever for holding it raised and so holding said second named switch open, said slide comprising a wire frame having side arms, and said rails having grooves in which said side arms slidably engage.

4. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator lever for holding it raised and so holding said second named switch open, said slide comprising a wire frame having side arms, and said rails having grooves in which said side arms slidably engage, and a strip mounted upon said wire frame and provided with an eyelet comprising said aperture.

5. A slide-controlled stop motion, comprising

8
a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator lever for holding it raised and so holding said second named switch open, said frame having a top member with an opening into which the bottom end of said tubular member engages, and a clamp strip mounted on said top member for clamping said tubular member in position.

6. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch, and means for guiding said traveling flexible element past said second named operator lever for holding it raised and so holding said second named switch open, said slide comprising a wire frame having side arms, and said rails having grooves in which said side arms slidably engage.

7. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, and means for guiding said traveling flexible element past said second named operator lever for holding it raised and so holding said second named switch open, said adjustment means including a screw rotatively supported through said tubular member, and a follower threadedly engaged on said screw and non-rotatively engaging said tubular member and connected with the top end of said spring.

8. A slide-controlled stop motion, comprising

tatively engaging said tubular member and connected with the top end of said spring, said screw having a projecting end with a knob by which it may be turned.

8. A slide-controlled stop motion, comprising a frame having parallel side rails, a slide having an aperture for a traveling flexible element to pass through and slidably mounted between said side rails, a tubular member mounted on the top of said frame, a coil spring of very fine wire having a large number of turns extending through said tubular member and having its bottom end connected with said slide for urging it upwards, adjustment means mounted on said tubular member and connected with the top end of said spring, a switch having an operator lever which is free to move downwards for closing the switch and said operator lever being normally engaged by said slide in its raised position for holding said switch open, another switch having an operator lever which is free to move downwards for closing the switch, means for guiding said traveling flexible element past said second named operator lever for holding it raised and so holding said second named switch open, a stud on the bottom of said frame for supporting said frame in various turned positions, and a support for said stud.

9. In a stop motion, a member, a traveling flexible element guide mounted on said member and having horizontal arms provided with forwardly directed ends and forwardly directed central portions, a switch mounted on said member, and a lever for operating said switch and being pivotally mounted on said member so as to fall forwards, said lever having a horizontal section adapted to be moved rearwards and aligned with said horizontal arms for the open position of said switch, said horizontal section having a rearwardly directed central portion and a rearwardly directed portion having a forwardly directed end into which said flexible element may be engaged by which said lever may be moved rearwards and by which said flexible element may be engaged behind the forwardly directed ends of said horizontal arms and then moved over to said aligned central portions.

10. In a stop motion, a member, a traveling flexible element guide mounted on said member and having horizontal arms provided with forwardly directed ends and forwardly directed central portions, a switch mounted on said member, and a lever for operating said switch and being pivotally mounted on said member so as to fall forwards, said lever having a horizontal section adapted to be moved rearwards and aligned with said horizontal arms for the opening position of said switch, said horizontal section having a rearwardly directed central portion aligned with said forwardly directed central portions and a rearwardly directed end portion having a forwardly directed end into which said flexible element may be engaged and by which said lever may be moved rearwards and by which said flexible element may be engaged behind the forwardly directed ends of said horizontal arms and then moved over to said aligned central portions, said guide comprising a strip of wire.
11. In a stop motion, a member, a traveling flexible element guide mounted on said member and having horizontal arms provided with forwardly directed ends and forwardly directed central portions, a switch mounted on said member, and a lever for operating said switch and being pivotally mounted on said member so as to fall forwards, said lever having a horizontal section adapted to be moved rearwards and aligned with said horizontal arms for the open position of said switch, said horizontal section having a rearwardly directed central portion and a rearwardly directed portion having a forwardly directed end into which said flexible element may be engaged by which said lever may be moved rearwards and by which said flexible element may be engaged behind the forwardly directed ends of said horizontal arms and then moved over to said aligned central portions, said switch comprising a contact arm and a cooperative contact connected with said lever and engageable with said contact arm.

EDWARD VOSSEN.
